UNITED STATES PATENT OFFICE.

ANDREW B. CROSS, OF DENVER, COLORADO.

COMBINED BEET PULLER AND TOPPER.

1,108,341.

Specification of Letters Patent. Patented Aug. 25, 1914.

Application filed April 18, 1913. Serial No. 761,942.

To all whom it may concern:

Be it known that I, ANDREW B. CROSS, a citizen of the United States of America, residing in the city and county of Denver and State of Colorado, have invented a new and useful Combined Beet Puller and Topper, of which the following is a specification.

This invention relates to improvements in combined beet pullers and toppers.

The object of the invention is to provide a machine of this character, comprising a wheel-supported frame, upon which is mounted a rotatable beet puller consisting of suitable supporting disks upon which are pivotally mounted co-operating pairs of beet pulling arms or levers, means being provided for operating said arms to clamp the tops and extract beets, and to release the tops at predetermined points in the rotative travel of the puller.

Further, to provide in connection with a rotatable beet puller, mechanism for raising the beet tops, and for guiding them between the pulling arms, in position to be clamped by said arms, and a knife arranged at a predetermined point in the rotative travel of the puller, for severing the tops from the beets, conveyers being provided to receive the beets and tops, independently, and to discharge them on one side of the machine.

These objects are accomplished by the mechanism illustrated in the accompanying drawings, in which:

Figure 1 is a side elevation of the improved beet puller and topper. Fig. 2 is a plan view of the same, parts being omitted to prevent confusion. Fig. 3, is a central transverse sectional view of the machine looking toward the forward end of the same. Fig. 4, is a plan view of a portion of the beet chute, showing the gate for determining the course of the beets. Fig. 5, is an enlarged view of the inner end of one of the gripping levers, showing anti-friction rollers thereon. Fig. 6, illustrates a modification of the roller shown in Fig. 5, together with the form of cam. Fig. 7, is a plan view of a modification of the beet topper. Fig. 8, is a detail sectional view showing a modification in the manner of connecting the gripping levers to the beet wheel. Fig. 9, is a top view of one of the cams for operating the gripping levers, and Fig. 10,

is a longitudinal sectional view through a portion of one of the beet top lifters. 55

Similar letters of reference refer to similar parts throughout the several views.

Referring to the accompanying drawings, the numeral 1 indicates a suitable frame which is preferably constructed of angle iron and which is provided at its rear end with depending brackets 2, upon the lower ends of which is mounted a shaft or axle 3, carrying supporting wheels 4. The front end of the frame is provided with a flat bearing ring 5, which rests upon a corresponding bearing ring 6, of a revolute support 7, which carries a shaft or axle 8, upon which are mounted supporting wheels 9. A bolt 10 passes axially through the rings 5 and 6, and is pivotally connected to the axle 8. A rod 10^A is supported in a bracket 10^B, above and rear of the bolt 10. The rod 10^A has a hand wheel 10^C at its upper end, and is also provided with a rigidly connected gear wheel 11, which meshes with teeth formed on the inner edge of the bearing ring 6. Thus, by turning the hand wheel, the front axle is turned and the machine is guided by the attendant to keep the pulling wheel in line with the row of beets to be pulled. 70

At a suitable position upon the frame 1, is rigidly mounted a transverse shaft 12, upon which is revolvably mounted a hub or drum 13, upon which are rigidly secured circular plates or disks 14, which are preferably about seven feet in diameter, and are out of contact with the ground. These plates are separated by a space of approximately nine inches, to permit the beet tops to pass between them, and their circumferential edges are provided with radial grooves or slots 15, of suitable depth, those in one plate being opposite those in the other plate, 95 to form co-operating pairs of slots, which correspond in number to the pairs of beet pulling arms 16, which are carried by the plates. The arms 16 are flat metal arms, having right angled projections 17, at their outer ends, which extend inwardly through the slots 15 of the plates 14, and upon the opposing edges of the projections 17, are secured or formed integral therewith clamping plates 18, the plates on each set of arms 105 being of such length that only a slight space

is left between them. The arms 16 are pivotally mounted intermediate of their ends, between pairs of angle plates 19, which are bolted to the circular plates 14, and their inner ends enter annular cam grooves 20, which may be formed in hubs 13^A, which are rigidly mounted on the shaft 12, but which are preferably formed by pairs of circular parallel plates, as illustrated, which are rigidly secured to the hubs 13^A. The grooves 20, formed by these plates, comprise portions 21, which are parallel with and adjacent to the respective plates 14, and portions 22, which are also parallel with but farther from the plates 14, than the portions 21, and the portions 21 and 22 are connected by short inclined portions 23. Thus, when the inner ends of the arms 16 are in the portions 21 of the grooves, their outer ends are widest apart, and when the said inner ends are in the portions 22 of the grooves, their outer ends lie close together, and their plates 18 are in clamping relation. The arms are thrown from one of these positions to the other, by contact of their inner ends with the short portions 23 of the grooves, whereby they are caused either to clamp or release the beet tops, as the case may be.

The hub or drum 13 is provided with 2 rows of sprocket teeth as shown, and is connected by chains 24, with a sprocket pulley 25, on a shaft 26, mounted on the frame 1, in front of the beet pulling wheel, and this shaft is provided, on opposite sides of the pulley 25, with sprocket wheels 27, which are connected by chains 28, with sprocket wheels 29, on the rear axle 3, by means of which motion is transmitted to the beet pulling wheel. The axle 3 is a revoluble axle, and the wheels may be connected to the axle by any suitable pawl and ratchet arrangement, such as commonly employed in agricultural machines, so that should the machine be backed, the shaft will remain stationary, and the beet wheel will not be rotated in a reverse direction.

Upon the chains 24 is secured a belt 24^A, and this belt 24^A is preferably a slatted belt, and is adapted to catch the beet tops as they are released by the pulling arms, and convey them out from between the plates 14. These tops are deposited by the belt 24^A upon an endless belt 30, mounted upon a frame 31, supported from the under side of the frame 1. The shafts of the end belt supporting rollers of the frame 31, are provided with bevel gear wheels 32, which mesh with bevel gear wheels 33, on the outer ends of shafts 34. These shafts 34 have sprocket wheels 35, on their inner ends, which are connected by chains 36, with loose sprocket wheels 37, on the shaft 26. The sprocket wheels 37 have toothed faces which are adapted to be engaged by clutches 38, which

26, so as to be slidable thereon, but rotatable therewith. The clutches are operated by levers 39, and when one or the other of them is in engagement with its sprocket wheel, the belt 30 is turned to the right or left, as the case may be, so that in whichever direction the machine is moving, the tops may be dropped on that side of the machine next the rows from which the beets have been pulled.

Depending from opposite sides of the frame 1, are suitable brackets 40, the lower ends of which are slightly in advance of the beet pulling wheel, and upon the lower ends of the brackets are revolvably mounted concavo-convex disks 41, which are oppositely inclined with respect to each other, being widest apart at their uppermost points. These disks are adapted to cut into the ground on each side of a row of beets, and loosen the beets to such an extent that they may be pulled by the clamps without liability of their tops being severed.

The tops are lifted from the ground and guided in between the plates 14 in position to be gripped by the clamps or pulling arms, in the following manner: Suspended from the frame 1, so as to lie at an inclination to the ground, in advance of the disks 41, are parallel roller-like members 42, having pointed forward ends. The forward portions of these members 42, are pivotally supported in the lower ends of hangers 43, which are secured at their upper ends to the frame 1. The rear ends of the members 42, terminate in short reduced neck portions 44, which fit revolvably in sleeves 45, at the lower ends of tubular hangers 46, which depend from the shaft 26.

The roller members 42, are rigidly mounted on shafts 47, which extend back between the plates 14 of the beet wheel, and similar roller members 48 are rigidly mounted on these shafts, and have short reduced neck portions 49, which fit revolvably in the rear ends of the sleeves 45, the members 48 extending to the opening between the plates 14. Upon the peripheral surfaces of the members 42 and 48, are formed auger-like ribs or beads, those on the right hand rollers being oppositely set from those on the left hand rollers. Upon the shafts 47 within the sleeves 45, are secured bevel gear wheels 50, which mesh with bevel gear wheels 51, on the lower ends of shafts 52, which extend up through the tubular hangers 46, and carry bevel gear wheels 53, at their upper ends, which mesh with similar wheels 54, on the shaft 26. Thus, motion is transmitted to the shafts 47, carrying the auger-like rollers, and which are turned outwardly in opposite directions from each other. These auger-like rollers lie on opposite sides of a row of beets, and as the machine advances, their pointed ends extend under and lift the beet

tops, which are thus guided back between the shafts or rods 47, and are held in position to be gripped by the clamping plates 18 at the outer ends of the levers 16.

5 About midway of the frame 1, and on opposite sides of the beet-pulling wheel, are secured uprights or standards 1^A, comprising angle bars 55 and 56, each of such pairs being connected at their upper ends, as shown. To the upper ends of these uprights is secured a resilient yoke-shaped beet guide 57, the open end of which is toward the rear. Upon the forward portion of this guide is secured a V-shaped knife 58, which is adapted to sever the beets from the tops, as they are forced in between the members of the said knife by the pulling wheel. The guide is adapted to be sprung or bent down to accommodate itself to the beet to be topped, some of which extend farther above the surface of the ground than others. Thus, a beet which extends above the ground will lie adjacent to or against the edges of the clamping plates 18, when its tops are clamped by the said plates, and this beet will naturally bend the forward end of the guide 57 down, as it passes through the same and between the blades of the V-shaped knife 58. The beets, however, which are level with or below the surface of the ground, will be a considerable distance from the edges of the clamping jaws when their tops are engaged by the said jaws, and obviously such beets will not tend to bring the guide 57 down. When the clamping plates grip the tops close to or so as to touch the beets, the large end of the beet and not the tops would be carried between the members of the beet guide, and would jam therein. In order to obviate this contingency, I secure on each member of the guide, adjacent to its rear end, a horizontally disposed U-shaped knife 59, the closed ends of which knives are toward each other. By this means, when beets thus clamped pass in between the rear ends of the guides, the knives 59 will cut U-shaped grooves in their opposite sides, which will permit them to pass between the members of the guide without jamming, and they will thus be more easily acted upon by the knife 58.

In order to facilitate the guiding and cutting operation, and also to remove the earth from the beets as they pass to the 55 knife 58, I secure above the beet guide spiral scrubbers, comprising parallel rollers 60, upon which are secured spirally wound brushes 61, the said spirals being oppositely turned with respect to each other. These 60 scrubbers lie at an angle parallel with the normal angle of the beet guide, and are rotatably supported at their forward ends in supports 62, which are attached to the bars 55 of the standards 1^A, and at their rear ends, in the members of an inverted U-

shaped support 63, the lower ends of which are secured to the bars 56 of the standards 1^A. The support 63 is high enough to let the beets pass under its upper closed end, and by forming the support thus, the rear ends of the rollers 60 are prevented from spreading. The rear ends of the rollers 60, having projecting shafts 64, which are connected to the upper ends of ordinary flexible shafts 65, which at their lower ends have bevel gears 66, which mesh with idle gears 67, which in turn mesh with bevel gears 68, on the upper ends of vertical shafts 69, having bevel gears 70 on their lower ends, which are driven by gears 71, on the rear axle 3. The various gears are arranged to drive the spiral scrubbers outwardly with respect to each other. When the beets are severed from the tops by the knife 58, they fall into a chute 72, which conveys them to an inverted V-shaped chute 73, the members of which extend out over and beyond the sides of the frame 1. A gate 74 is hinged at its forward end to the front side of the chute 73, and at the apex of the same, so that it can be swung to the right or left, and rest against either one side or the other of the chute 72, so as to guide the beets into the right or left member of the chute 73, as will be understood by reference to Fig. 4. The ends of the levers 16, which enter the cam grooves 20, are provided with anti-friction rollers 75, having axial recesses 76, which extend in from their opposite ends, leaving a centrally apertured abutment wall 77, through which the reduced extremity of the lever passes. A spring 78 is interposed between one side of the abutment and a shoulder 79, near the end of the lever, and a similar spring is interposed between the opposite side of the abutment and a washer 80, which is held on the end of the lever by a nut 81. In this way the rollers 75 are prevented from climbing on the walls of the cam grooves, as the lever moves in and out.

A modification of the cam and roller is shown in Fig. 6. In this modification, the outer edges of the walls of the cam groove are introverted as shown at 82, to prevent the withdrawal of the rollers 83, which may be inserted at some point when the introverted edges are recessed for the purpose. The springs 78 are eliminated and the reduced inner end of the lever slides through an axial aperture in the roller, as the levers are rocked on their pivots.

In Fig. 7, a modification of the cutting or topping knife is shown. In this modification the same form of beet guide is employed as is shown in Fig. 2, but the V-shaped knife is dispensed with, and a pair of co-operating cutting disks 84 are employed. These disks have spindles which are mounted in bearings on the members of the guide, and the free ends of the spindles 125

are connected to flexible shafts 85, which are connected to the rear axle in the manner above described.

In Fig. 8, is shown a modification in the manner of attaching the clamping levers to the sides of the circular plates 14. In this modification, I connect the lever to the plate 14, by a spring 86, which will not only permit the lever to give, if its outer end should strike an obstruction, but it also permits the levers to clamp the beet tops with a yielding pressure, by which the said levers can accommodate themselves to bunches of stalk of varying bulk. A seat 87 is supported rear of the steering wheel 10^c, and the attendant occupying the same can also shift the gate 74 in the beet chute 73, to properly direct the beets as they fall from the knife.

In operation, the machine is drawn along the field over a row of beets, and as it advances the beet tops are lifted by the auger-like lifters, and conveyed back between the plates 14, which carry the clamping or gripping levers 16; the disks 41 cutting the ground on each side of the row of beets. The cam is so set that as the gripping levers in their travel come to a position on opposite sides of the beet tops to be gripped, the coöperating pairs of levers are simultaneously closed upon the said tops, and as the pulling wheel further rotates, the beet is extracted, and carried around and into the beet guide, where its progress is augmented, and the earth removed therefrom, by the spiral scrubbers 61; and as it passes between the blades of the knife 58, it is severed from the tops, and falls into the chute 72, and thence into the chute 73, the gate 74 determining upon which side of the machine it is delivered. As the wheel rotates and the gripping levers reach a point slightly beyond the point where the beet was severed, the cam opens the said levers and the tops drop down between the plates 14 and upon the slotted belt 24^a, which drops them upon the conveyer 30, by which they are delivered on the right or left side of the machine, as the case may be, it being understood that when one of the clutches 38 is in engagement with the adjacent sprocket wheel 37, the other clutch is out of engagement with its sprocket wheel. By properly manipulating the steering wheel 10^c, the machine may be so guided as to cause the top lifters 42, always to straddle a row of beets as the machine advances.

Having described my invention, what I claim as new and desire to secure by Letters Patent, is:

1. The combination with a rotatable series of beet gripping levers, of a V-shaped beet guide, operatively supported in the path of said levers, a V-shaped knife upon the closed end of said guide, and opposing horizontally disposed U-shaped knives on said guide adjacent the extremities thereof, the closed ends of which are toward each other. 60

2. The combination with a rotatable series of beet gripping levers arranged in coöperating pairs, and means for opening and closing said pairs of levers at predetermined points in their rotative travel, of a resiliently-yielding beet guide operatively supported at a predetermined point in the path 70 of said levers, a topping knife on said guide and gouges at the entrance of said guide, and secured thereto, for removing portions from opposite sides of beets.

3. The combination with a rotatable series 80 of beet gripping jaws arranged in coöperating pairs, a guide and a topping knife on said guide, of parallel rotatable beet scrubbers operatively supported above said guide, and means for operating them.

4. The combination with a rotatable series of beet gripping levers arranged in coöperating pairs, a beet guide supported in the path of said levers, and a topping knife on said guide, of spaced parallel rollers supported above and adjacent said beet guide, having spirally arranged brushes thereon, and means for rotating said rollers in opposite directions. 85

5. In a beet puller and topper, a rotatable 95 series of radially disposed gripping levers arranged in coöperating pairs, means for automatically closing said levers at predetermined points in their rotative travel, for holding them closed for a fixed period and 100 for opening them and holding them open for a fixed period, the outer ends of said levers being out of contact with the ground, a resiliently yielding V-shaped beet guide supported in operative relation to the path 105 of the clamping ends of the lever, and a V-shaped knife on said beet guide.

In testimony whereof I affix my signature in presence of two witnesses.

ANDREW B. CROSS.
